ALBERT EDMUND HUDSON, OF CALGARY, ALBERTA, CANADA.

SANDING DEVICE.

1,113,557.

Specification of Letters Patent.

Patented Oct. 13, 1914.

Application filed December 1, 1913. Serial No. 804,055.

To all whom it may concern:

Be it known that I, ALBERT EDMUND HUDSON, a subject of the King of Great Britain, and resident of Calgary, in the Province of Alberta, Dominion of Canada, have invented certain new and useful Improvements in Sanding Devices, of which the following is the specification.

This invention relates to improvements in sanding devices such as are used in locomotives, and the object of the invention is to automatically apply sand to the rails when the air brake is being applied to the train, such application of sand being performed simultaneously with the operation of the brakes, and it consists essentially of the improved valve and pipe arrangement hereinafter particularly described by reference to the specification and drawing.

20 The figure is a view of the device, part of which is in section, showing the automatic controlling valve.

Referring to the drawing, D represents the improved sanding device which is connected directly to the air reservoir through the pipe leading from the T-piece and on that side of it directly opposite the pipe 76. The air reservoir which is of the usual type found in railway practice and not forming a part of this invention, except in so far as to be a source of supply, is not described or shown.

70 represents the sanding pipe extending to the usual sander (not shown) and the direct admission of compressed air to such pipe is controlled by the hand valve 71. A bypass is provided according to the present invention by means of a casing member 72 having two bores 73 and 74 at right angles to each other, the bore 73 being connected by piping 74^a with the sanding pipe 70 and the bore 74 being connected on one end to the main reservoir by piping 75, the main reservoir also being connected to the sand pipe 70 by the piping 76. The opposite end of the bore 74 also connects with the train line by piping 77. A piston valve 78 is provided in the bore 74 and is formed with an enlarged head 79 adapted to fit an enlarged portion 80 at one end of the bore, the normal position being as shown in Fig. 9 when the reduced portion 81 of the piston valve normally closes the bore 73 owing to the fact that the pressure in the train line pipe and main reservoir bal-

ance it in this position, the difference in area of the ends of the piston valve causing this balance to take place.

The operation of the device is as follows: When the brakes are applied the pressure 60 in the train line is relieved and the piston valve 81 moves toward the enlarged end 80 so uncovering the bore 73, the air passing from the reservoir through the pipe 75, 74^a and 70 to the sander from which the sand 65 is delivered in the usual way. On releasing the brakes the air pressure in the train line is re-adjusted whereupon the piston valve 81 moves in the direction of the end 74 thereby closing the bore 73. 70

If it is found desirable to apply sand to the rails at any time other than when the brakes are in operation the air pressure is passed directly from the air reservoir to the sander by releasing the hand wheel valve 71. 75

As many changes could be made in the above construction and many apparently widely different embodiments of my invention, within the scope of the claims, constructed without departing from the spirit 80 or scope thereof, it is intended that all matter contained in the accompanying specification and drawings shall be interpreted as illustrative and not in a limiting sense.

What I claim as my invention is:

1. A sanding device adapted to be operated by the reduction of pressure in the train line pipe and comprising a casing, bores in said casing and a piston valve movable transversely across one of said bores, 90 and balanced on opposite sides by the pressure from the main reservoir and the train line pipe, the bores being so arranged that on movement of the piston valve by reduction of pressure in the train line pipe the 95 sander will be operated.

2. In a sanding device, the combination with the sanding device and a valve controlling the passage of air from the main reservoir to the sanding pipe, of a bypass, 100 a valve movable transversely across said bypass, such valve being controlled by the pressure in the train line pipe, substantially as described.

In witness whereof I have hereunto set 105 my hand in the presence of two witnesses.

ALBERT EDMUND HUDSON.
